COMBINATION MIST GENERATOR AND MANIFOLD ASSEMBLY FOR LUBRICATION SYSTEM

James H. Yon, Jr., Charlotte, N.C., assignor to Jett Manufacturing Corporation, Charlotte, N.C., a corporation of North Carolina

Filed Oct. 28, 1968, Ser. No. 14,200

Term of patent 14 years

Int. Cl. D15—08

U.S. Cl. 46—1

FIG. 1 is a front elevation view of a combination mist generator and manifold assembly for lubrication system embodying my new design; and

FIG. 2 is a plan view of the combination mist generator and manifold assembly for lubrication system of FIG. 1.

The broken lines are for illustrative purposes only.

I claim:

The ornamental design for combination mist generator and manifold assembly for lubrication system, as shown and described.
